REFRIGERATING APPARATUS

Richard S. Gaugler, Dayton, Ohio, assignor to
General Motors Corporation, Dayton, Ohio, a
corporation of Delaware

Application May 31, 1941, Serial No. 395,944

14 Claims. (CL 62—119.5)

This invention relates to refrigerating apparatus and more particularly to household absorption refrigerating machines.

The cooling elements of household absorption refrigerating machines have been somewhat complicated and costly. It is an object of my invention to provide a cooling unit of improved construction which is more simple and less expensive than prior cooling units.

It is another object of my invention to provide an improved high humidity compartment in household absorption machines.

It is another object of my invention to provide an economical efficient arrangement of primary and secondary cooling units in an absorption system.

In absorption machines, it has been customary to place a screen or screens within the passages of the evaporator and other means in the absorber in order to increase the amount of liquid surface exposed to the gas and vapor. The liquid by capillary action spreads over the surface of the screens. I find that there is poor heat transfer between the walls of the passages and the screens so that the efficiency of evaporation is reduced.

It is an object of my invention to provide a capillary means forming an integral part of the wall surface of the passages of the absorber and/or the evaporator by which liquid collected in the bottom of the passages is spread by a capillary action over the entire wall surface of the passages.

In the past, in absorption machines the condenser has been located in the upper part of a flue at the back of the cabinet which at its lower end received waste heat from the absorber and generator as well as the products of combustion of the gas burner used to heat the generator. In such an arrangement, the air rising in the flue for cooling the condenser was already warm so that the condenser was not contacted and cooled by air at room temperature.

It is an object of my invention to provide a cooling arrangement for refrigerating systems wherein air at room temperature is used for cooling the condenser.

It is an other object of my invention to provide an improved condenser for absorption systems in which condensation is assured under varying temperature conditions.

Further objects and advantages of the present invention will be apparent from the following description, reference being had to the accompanying drawings, wherein a preferred form of the present invention is clearly shown.

In the drawings:

Fig. 1 is a central vertical sectional view through an absorption refrigerator with the door, the refrigerating system and a portion of the liner in elevation and with the vertical partition walls removed, disclosing one form of my invention;

Fig. 2 is a view of the back of the cabinet with the rear wall of the flue removed;

Fig. 3 is a plan view of the cooling unit;

Fig. 4 is a sectional view of the cooling unit taken along the line 4—4 of Fig. 3;

Fig. 5 is a view in side elevation of the cooling unit;

Fig. 6 is a sectional view taken along the line 6—6 of Fig. 3;

Fig. 7 is a view taken along the line 7—7 of Fig. 3;

Fig. 8 is a sectional view taken along the line 8—8 of Fig. 3;

Fig. 9 is a sectional view taken along the line 9—9 of Fig. 3;

Fig. 10 is an enlarged longitudinal sectional view of the tubing shown in Figs. 3 to 5;

Fig. 11 is an enlarged transverse sectional view of the same tube;

Fig. 12 is a sectional view taken along the line 12—12 of Fig. 3;

Fig. 13 is a sectional view smaller but in other ways corresponding to the sectional view shown in Fig. 11 of a modified form of capillary surface in the tubing of the cooling unit and/or absorber.

Fig. 14 is a diagrammatic view of the absorption refrigerating system;

Fig. 15 is a fragmentary enlarged section through the rear wall of the cabinet taken substantially on the line 15—15 of Figs. 3 and 4; and

Fig. 16 is a rear view of the inner liner member with the secondary refrigerant circuit wrapped around it.

Briefly, I have shown an absorption refrigerator characterized by a flat cooling unit formed of tubing shaped in serpentine fashion to which is bonded a metal plate for receiving ice trays. The portion of the refrigerator containing the cooling element is separated from the lower portion by a transparent plate of poor heat conductivity. This lower compartment, formed by the glass plate, is cooled by a secondary refrigerant circuit surrounding the compartment which is connected to the secondary condenser which in turn is clamped to the gas outlet portion of the cooling unit. The interior of the tubing used to make the evaporator is provided with a capillary means so designed as to accomplish intimate

thermal contact between the surface of the liquid

refrigerant where refrigeration is produced and the walls of the tubing. For example, the interior of the cooling unit may be provided with helical grooves which are square in cross-section as shown in Fig. 10. These grooves have their parallel walls sufficiently close together that they form a capillary cavity so that liquid will be drawn by capillary attraction from the bottom of the tube all the way around each of the grooves. In modified form, this capillary surface is provided by providing sintered metal upon the interior wall of the tube. This sintered metal is porous and its pores are capillary size so that liquid is distributed throughout the surface of the sintered metal, as in the case of the grooves. A diagonal partition separates the air flowing from the generator and absorber of the back of the cabinet from the air flowing from the condenser. The condenser is of a peculiar construction in which the vapor inlet and the gas outlet are connected to inclined condensing passages which in turn connect at their lower ends to a common liquid receiver.

Referring now to the drawings and more particularly to Fig. 1, there is shown an insulated refrigerator cabinet generally designated by the reference character 20 and provided with inner liner member 22 surrounded by insulation 24. A cabinet door 26 closes the food compartment. The food compartment is divided into an upper freezing compartment 28 and a lower high humidity compartment 30 by a dividing shelf 32 preferably formed of a sheet of transparent material which may be sealed to the walls of the compartment. If desired a seal may also be provided between the front edge of the shelf and the rear face of the door 26 so as to substantially completely seal the compartments from each other.

The upper compartment 28 contains a primary evaporator 34. This primary evaporator 34 is primarily formed of tubing bent into a serpentine shape, as shown in Fig. 3. In addition to being formed into a serpentine shape as shown in Fig. 3, this tubing is also flattened in varying amounts which decrease uniformly from the front edge to the rear edge of the evaporator as is illustrated by the sections shown in Figs. 6 to 8 inclusive. In addition, the portion of the tubing designated by the reference character 36 is provided with a sloping wedge 38 which is U-shaped in cross-section and has its largest end adjacent to the rear of the evaporator so as to provide a thermal connection between this portion of the tubing and the metal plate 40 which forms the top surface of the evaporator. This metal plate 40 is bonded metallically directly to the evaporator tubing as shown in Figs. 7 and 8 and through the wedge 38 as shown in Fig. 9. With this flattening of the tubing and the use of the wedge 38 the portion of the tube beneath the plate 40 has a uniform downward slope to the end 42 which serves as the inert gas inlet of the evaporator tubing.

Any unevaporated liquid collecting in the end 42 of the evaporator tubing may be drained by the tube 37 into the gas tube 92 which carries it to the absorber receiver.

The evaporator 34 is supported at one end from the back plate 124 by a set of U-shaped brackets. One of these U-shaped brackets 126 is fastened to the back plate 124 while the other bracket 35 is welded to the portion 44 of the evaporator tubing in the insulation space. These brackets are connected together by a bolt 39.

The other end of the evaporator 34 is supported by the connections of the ends of its tubing with the gas interchanger 88 which is fastened to the back plate 124.

The end 44 which serves as the liquid refrigerant inlet and the inert gas outlet of the evaporator tubing is located within the insulation space and is provided with a connecting plate 46 to which is clamped a secondary plate 48 by means of the screws 50 and 52. A cover 23 closes the opening in the back of the inner liner 22 which opening provides access to the insulation space where the end 44 of the evaporator 34 and the plates 46 and 48 are located. Bonded to this secondary plate 48 is the condenser portion 54 of the secondary refrigerant circuit. This condenser portion 54 slopes downwardly parallel to the portion 44 of the evaporator tubing to which it is clamped.

Prior to forming the tubing into the serpentine shape the evaporator tubing is threaded on the inside by a tool which forms the capillary grooves 56 (see Figs. 10 to 12). These capillary grooves 56 have square bottoms and parallel sides which are sufficiently close together to cause any liquid in the tube to be drawn into the grooves by capillary attraction. This capillary attraction will cause liquid to spread throughout the grooves in the tubes so that when hydrogen and liquid flow through the tubing there will be a large amount of liquid surface provided for contact with the inert hydrogen. This improves the efficiency of evaporation since the configuration which provides capillary action within the tube is an intimate part of the metal wall of the tube so that there is the maximum heat transfer between the outer walls of the tube and the liquid held in capillary attraction.

In Fig. 13 there is shown another way in which the capillary surface may be in intimate thermal contact with the walls of the tubing. In Fig. 13 the capillary surface is formed by a layer of sintered metal 58, such as sintered iron, which is bonded to the interior of the tube by applying the powder prior to sintering to the interior walls of the tube, after which the powder, which has been applied to the walls of the tube, is sintered by placing the tubing in a non-oxidizing atmosphere for a sufficient length of time at a sufficiently high temperature. For example, the sintering may be carried out at temperatures around 2000° F. for periods from 15 minutes to an hour. Preferably the tubing is formed of steel and a sintered material is formed from powdered iron which includes some ferrous powder. For the sintered wall coating, I prefer to use the process and materials described in the Lenel Patent No. 2,226,520, dated Dec. 24, 1940. However, other processes and materials may be used if desired. For example, the metal particles may be bonded to the wall of the tubing and to each other by another metal or other material such as tin or solder. This inner coating of sintered material provides a capillary layer which will distribute any liquid in the bottom of the tube throughout the inner wall surface of the tube until the pores of the sintered metal are saturated. The metal plate 40 may also be made of iron or steel and may be bonded to the tubing by copper hydrogen brazing, welding, soldering or other suitable means. If the copper-hydrogen brazing process is used this could be performed at the same time when the sintering is performed.

The secondary condenser 54 drains into the secondary evaporator 60 which is provided with

serpentine loops extending over the outside of the bottom, back, and side walls of the lower compartment 30. Since the inert gas outlet portion 44 of the cooling unit is at a much higher temperature than other portions thereof, the secondary evaporator will be maintained at a comparatively high refrigerating temperature so that a relatively high humidity will be maintained in the lower compartment 30. The temperature of the walls of the lower compartment 30 and the secondary evaporator 60 is sufficiently low to provide adequate refrigeration.

The evaporator 34 is supplied with liquid refrigerant from a novel form of condenser 64. This condenser 64 is mounted upon the upper portion of the rear wall of the cabinet and is provided with an inlet header 68 which connects to a plurality of parallel tubes 70 which slope downwardly at an angle and terminate in a liquid receiver 68 at the lowest portion of the condenser. Extending upwardly at an angle from the liquid receiver 68 are a plurality of parallel tubes 72 which extend upwardly to a point adjacent inlet header 66, after which they curl downwardly and terminate in a gas header 74. Transverse fins 76 are distributed uniformly over both groups of tubes. If desired, these fins may be divided to provide a separate section for each bank of parallel tubes. The liquid receiver 68 is connected by a liquid tube 78 to the refrigerant inlet and inert gas outlet portion 44 of the evaporator tubing. The inlet header 66 is connected by tubing 80 which extends downwardly to the generator structure. The gas outlet header 74 is connected by tubing 84 to a hydrogen tube 86 which connects to the gas interchanger 88 which in turn connects to the tubes 90 and 92. The lower end of the tube 92 connects to the top of the absorber receiver 111, while the lower end of the tube 90 connects to the upper end of the absorber 94.

Beneath the insulated portion of the cabinet there is a generator 101 provided with a standpipe 103 and a vapor lift pump 105 which discharges through a tube 106 into the upper portion of the standpipe 103. The vapor discharged from the vapor lift tube 106 flows through the first part of the pressure equalizing tube 108 to the connecting tube 110 which discharges its vapor beneath the liquid level in the lower end of the slightly inclined analyzer 112. The upper end of the analyzer 112 is provided with a standpipe 114 containing baffles forming a rectifier. This standpipe 114 is connected to the vapor conduit 80 which in turn connects to the condenser inlet 66. The lower end of the pressure equalizing tube 108 connects to the highest point of the weak liquor conduit 102 extending from the generator 101 to the top of the absorber 94 to prevent gas or vapor from collecting in this conduit. The lower end of the pressure equalizing tube 108 contains a column of weak liquor substantially at the same level as the level of liquid in the stand pipe 103. This seals the lower end of the pressure equalizing tube 108. The liquid from the generator passes through the liquid conduit 102 which extends through the slightly inclined analyzer 112 and discharges the liquid from the generator through the exposed portion 113 into the lower end of the pressure equalizing tube 108. The lower end of the pressure equalizing tube 108 connects to and discharges the liquid into a tube 157 which extends through the liquid heat interchanger 107 and connects to a precooler 109 which in turn

discharges into the upper end of the absorber 94. The absorber 94 preferably is provided with capillary grooves in its inner wall surface such as the grooves 56 shown in Fig. 11 for the purpose of spreading by capillary action the weak absorption liquid throughout the inner wall surface of the absorber. Instead of the capillary grooving, the sintered metal layer may be bonded to the inner walls of the absorber as shown in Fig. 13. The absorber 94 is provided with a receiver 111 at its outlet which in turn is connected through the connection 161 to the liquid interchanger 107. The outer portion of the liquid interchanger 107 connects through the liquid conduit 159 with the upper portion of the slightly inclined analyzer 112. The lower end of the analyzer 112 is connected by the liquid conduit 99 to the rear portion of the generator to supply the generator with rich liquor.

Upon the back of the cabinet there is provided a flue formed of the extensions 113 and 115 of the side walls of the cabinet and the rear covers 117 and 119 which form the back wall of the flue. The flue is divided into two parts by a diagonal metal dividing wall 121 which extends from the left end of the absorber to the right end of the condenser as shown in Fig. 2. This then provides a flue 123 between the dividing wall 121 and the extension 115 and a second flue 125 between the dividing wall 121 and the extension 113. Vertical metal walls 127 and 129 are provided at opposite ends of the absorber. Louvers 131 are provided in the upper portion of the extension 115 while louvers 133 are provided in the lower portion of the extension 113.

By this arrangement all of the waste heat and products of combustion of the absorber and the generator pass upwardly through the flue 123 and are discharged through the louvers 131 without contacting the condenser 64. This provides a flue of ample proportions for creating a natural draft for cooling both the absorber and the generator. Provision of a condenser in such a flue would not add to the circulation through the flue. By locating the condenser 64 in a separate flue 125, the air at room temperature contacts the condenser 64 without being warmed by any other elements of the system. Thus the condenser, excepting for differential due to heat transfer, may be maintained at room temperature. This arrangement greatly increases the efficiency of the system.

My improved form of condenser also increases the efficiency since the warm vapor from the analyzer first passes through the upper bank of tubes of the condenser and normally substantially all the vapor is condensed in this upper bank of tubes and is collected in the liquid receiver 68 and is thence conducted through the liquid tube 78 to the primary evaporator. However, if the vapors should not be sufficiently cooled to be liquefied in the upper pass, when they reach the receiver 68 they will ascend the lower pass 72 where they will be further cooled and then will continue to ascend until they are liquefied after which they will flow downwardly in liquid form through the lower pass to the liquid receiver 68.

In the absorber 94, the cooled weak liquor flows downwardly and removes ammonia from the mixture of ammonia and inert hydrogen gas which flows upwardly through the absorber 94. The inert gas arrives at the upper end of the absorber substantially free of ammonia. This inert gas then rises through the tube 90 to the

gas interchanger 88 where it is further cooled and then enters the lower portion 36 of the evaporator tubing. In the evaporator tubing, the liquid refrigerant is distributed throughout the capillary wall surface of the tubing and the liquid refrigerant evaporates into the inert gas. The inert gas will continue upwardly through the evaporator tube while the liquid refrigerant flows downwardly therein. The amount of refrigerant in the inert gas will increase as the inert gas flows upwardly through the evaporator tubing. This will cause the evaporating temperature to rise since the partial pressure of the refrigerant in the hydrogen will increase as it flows toward the upper end of the evaporator tubing. Since the greater portion of the evaporator tubing is bonded thermally to the metal plate 40 it will be maintained at somewhat the same temperature.

However, the final portion of the evaporator tubing which is located in the insulation space, is not bonded thermally to the plate 40, so that this portion will reach a higher temperature. Also, the secondary circuit will supply heat at a higher temperature level than is supplied in the compartment 28 so that the temperature of that portion within the insulation space will be maintained at a higher temperature level. Refrigeration performed at this temperature level could not be used for freezing purposes or for cooling the compartment 28. However, refrigeration at this temperature level serves very desirably in providing refrigeration of the lower compartment at a high temperature through the large surface, mainly the surface of the liner, so that there is only a small temperature differential between the air in the compartment 30 and the secondary condenser 54 and the upper portion 44 of the evaporator tubing. By this arrangement of cooling the compartment 30 at a higher temperature level and conducting this heat to the outlet portion of the evaporator, additional refrigeration can be accomplished with the inert gas which is already rich in refrigerant vapor. Furthermore by this introducing an additional amount of refrigerant vapor into the inert gas, the saturated inert gas is made heavier. This increases the rate of circulation throughout the inert gas circuit which takes place by reason of the difference in density between the inert gas which has been robbed of refrigerant and inert gas which is saturated with refrigerant. This saturated inert gas leaves the evaporator 34 and passes downwardly through the gas interchanger 88 and the gas tube 92 to the receiver 111 located at the bottom of the absorber from which point it flows upwardly through the absorber 94.

While the form of embodiment of the invention as herein disclosed, constitutes a preferred form, it is to be understood that other forms might be adopted, all coming within the scope of the claims which follow.

What is claimed is as follows:

1. Absorption refrigerating apparatus comprising a cabinet, a system for cooling the interior of the cabinet including a cooling unit in heat exchange relation with the interior of the cabinet and a generator, a condenser, and an absorber outside the cabinet, said cabinet being provided with a vertical flue upon its back wall, said generator and absorber being located adjacent the bottom of the flue, said condenser being located adjacent the top of the flue, a dividing member extending diagonally upwardly to

divide the flue into two paths of flow, the one division of the flue being wide at the top and having the condenser located at its upper end, the second division of the flue being wide at the bottom and having the generator and the absorber located at its lower end.

2. Absorption refrigerating apparatus comprising a cabinet having an inner liner enclosing a compartment to be cooled, means within the liner for dividing said compartment, insulating means surrounding the inner liner, an absorption cooling unit having an inert gas outlet portion located outside said liner within said insulating means and a second portion arranged serially with respect to the initial portion located in one of the divisions of said compartment for receiving refrigerant liquid discharged from said initial portion, generating and absorbing means for supplying refrigerant to said inert gas outlet portion and for circulating a gas inert with respect to said refrigerant through said cooling unit in such a direction that it leaves at the inert gas outlet, a secondary refrigerant system having an evaporating means mounted in heat exchange relation with the outside of said inner liner and a condensing means in heat exchange relation with said inert gas outlet portion.

3. Absorption refrigerating apparatus including an absorption cooling unit in the form of an elongated conduit means having metal walls and having an inert gas inlet at one end and a gas outlet at the other end, the metal walls of said conduit means adjacent the gas inlet being adapted for arrangement in heat exchange relation with a first medium to be cooled, a secondary refrigerating system for maintaining a second medium at a higher temperature than the first, said secondary refrigerating system having its condensing portion in heat exchange relation only with the portion of the metal walls adjacent the gas outlet of the cooling unit for increasing the evaporation of refrigerant into the inert gas as it leaves the cooling unit.

4. Absorption refrigerating apparatus including an absorption cooling unit in the form of an elongated conduit means having metal walls and having an inert gas inlet at one end and a gas outlet at the other end, the metal walls of said conduit means adjacent the gas inlet being adapted for arrangement in heat exchange relation with a first medium to be cooled and being provided with means for increasing the area of heat exchange relation with said first medium, wall means for separating a portion of the metal walls of said passage adjacent said gas outlet from said first medium to be cooled so as to be out of direct contact with said first medium, a secondary refrigerating system for maintaining a second medium at a higher temperature than the first, said secondary refrigerating system having its condensing portion in heat exchange relation only with said portion of the metal walls adjacent the gas outlet of the cooling unit for increasing the evaporation of refrigerant into the inert gas as it leaves the cooling unit.

5. A heat transfer device comprising an enclosed container means only partially filled with a volatile liquid leaving a space for vapor above the surface of the liquid, the interior walls of the container means being of metal and being provided with a porous capillary structure of sintered iron extending upwardly from the surface of the volatile liquid for conducting the

liquid upwardly from the surface by capillary action, said capillary structure having a portion of its surface exposed in the vapor space saturated with the liquid to expose the volatile liquid in the upper portion of the vapor space.

6. A heat transfer device comprising an enclosed container means only partially filled with a volatile liquid leaving a space for vapor above the surface of the liquid, the interior of the container means being provided with a porous capillary structure extending upwardly from the surface of the volatile liquid for conducting the liquid upwardly from the surface by capillary action, said capillary structure having a portion of its surface exposed in the vapor space saturated with the liquid to expose the volatile liquid in the upper portion of the vapor space, said capillary structure being in the form of sintered powdered metal.

7. Absorption refrigerating apparatus including a container, means for supplying liquid refrigerant to the container in an amount insufficient to completely fill the container to leave a space above the surface of the liquid and also for circulating an inert gas through the container, said container being provided with a porous capillary structure of sintered metal in contact with the refrigerant liquid and extending upwardly from the liquid surface into contact with said gas, said refrigerant liquid saturating said structure by capillary action to provide an increased area of contact between the refrigerant liquid and the gas.

8. Absorption refrigerating apparatus including a cooling unit, means for supplying sufficient liquid refrigerant to partially fill but insufficient to completely fill the cooling unit and also for circulating an inert gas through said cooling unit, said cooling unit being provided with a porous capillary structure of sintered metal having a portion in contact with the liquid refrigerant and extending upwardly from the liquid surface into contact with said gas, said liquid refrigerant saturating said structure by capillary action to increase the area of contact between the refrigerant liquid and the gas.

9. Absorption refrigerating apparatus including a cooling unit, means for supplying sufficient liquid refrigerant to partially fill but insufficient to completely fill the cooling unit and also for circulating an inert gas through said cooling unit, said cooling unit being provided with a porous capillary structure of sintered metal having a portion in contact with the liquid refrigerant and extending upwardly from the liquid surface into contact with said gas, said liquid refrigerant saturating said structure by capillary action to increase the area of contact between the refrigerant liquid and the gas, said capillary structure being in the form of a continuous coating upon the interior walls of the cooling unit.

10. Absorption refrigerating apparatus including an absorber, means for supplying weak liquor in an amount insufficient to completely fill the absorber and also for circulating an inert gas charged with refrigerant vapor through the ab-

sorber for transferring the vapor to the liquor, said absorber being provided with a porous capillary structure of sintered powdered metal having a portion in contact with the weak liquor

5 and extending upwardly from the liquid surface into contact with said inert gas charged with refrigerant vapor, said weak liquor saturating said structure by capillary action to increase the area of contact between the weak liquor and the gas.

11. Absorption refrigerating apparatus including an absorber, means for supplying weak liquor in an amount insufficient to completely fill the absorber and also for circulating an inert gas

15 charged with refrigerant vapor through the absorber for transferring the vapor to the liquor, said absorber being provided with a porous capillary structure of sintered powdered metal having a portion in contact with the weak liquor

20 and extending upwardly from the liquid surface into contact with said inert gas charged with refrigerant vapor, said weak liquor saturating said structure by capillary action to increase the area of contact between the weak liquor and the

25 gas, said capillary structure being in the form of a continuous coating upon the interior walls of the absorber.

12. A heat transfer device comprising an enclosed container means only partially filled with a volatile liquid leaving a space for vapor above the surface of the liquid, the interior of the container means being provided with a structure having capillary grooves extending upwardly from the surface of the volatile liquid into the vapor space, said capillary grooves having substantially parallel walls spaced sufficiently close together that the volatile liquid will be attracted to all parts of the grooves by capillary action.

13. A heat transfer device comprising an enclosed container means only partially filled with a volatile liquid leaving a space for vapor above the surface of the liquid, the interior walls bordering the vapor space of the container means

35 being of metal and being provided with a capillary surface forming an integral part of the wall structure of the container means, said capillary surface extending from the surface of the liquid upwardly to carry the liquid through capillary action up over the wall surface bordering the vapor space to keep this wall surface wetted with liquid.

14. A heat transfer device comprising an enclosed container means only partially filled with a volatile liquid leaving a space for vapor above the surface of the liquid, the interior walls of the container means bordering the vapor space

55 being of metal and being provided with a capillary metal coating of porous sintered iron forming an integral part of the metal wall structure, said capillary surface extending from the surface of the liquid upwardly to carry the liquid through capillary action up over the wall surface bordering the vapor space to keep this wall surface

60 wetted with liquid.
